DESIGN FOR AN ASTRONOMICAL DEVICE

Thomas T. Harvey, Denver, Colo., assignor of
fifty per cent to Dorothy Smith Harvey and
fifty per cent to Ruth Genung Millar, both of
East Orange, N. J.

Application September 8, 1941, Serial No. 103,222

Term of patent 14 years

To all whom it may concern:

Be it known that I, Thomas T. Harvey, a citizen of the United States and a resident of Denver, Colorado, whose post office address is c/o John A. Millar, Laboratory Associates, Inc., 22 Plane Street, Newark, New Jersey, have invented a new, original, and ornamental Design for an Astronomical Device, of which the following is a specification, reference being had to the accompanying drawing, forming part hereof, and in which

Fig. 1 is a perspective view of an astronomical device showing my new design; and

Fig. 2 is a top view.

The abbreviations, words and numerals and their arrangement on the design are merely illustrative.

I claim:

The ornamental design for an astronomical device substantially as shown and described.

THOMAS T. HARVEY.
